UNITED STATES PATENT OFFICE.

ALLIOTT VERDON ROE, OF MANCHESTER, ENGLAND.

BELT-SUPPORT FOR AVIATORS.

1,239,041.

Specification of Letters Patent.

Patented Sept. 4, 1917.

Application filed September 19, 1916. Serial No. 121,017.

To all whom it may concern:

Be it known that I, ALLIOTT VERDON ROE, a subject of the King of Great Britain, residing at Manchester, England, have invented certain new and useful Improvements in Belt-Supports for Aviators, of which the following is a specification.

This invention relates to improvements in the construction of belts or safety harness, for the use of a pilot, or other aviator, especially on an aeroplane.

The object of the invention is to construct a belt which can be easily adjusted both for vertical and horizontal position in regard to the car of the aerial machine, and which also may quickly be disconnected at any time from the person of the aviator.

Though not strictly a belt, "belt" is the term commonly used for this device, and accordingly this term will be used herein. Moreover, although the harness is really a broad pad located across the chest of the aviator, many aviators prefer a complete belt, and a connecting strap around the back of the wearer and attached to the pad in front, may be used if desired.

My invention, stated in general terms, consists of means designed for enabling a pilot to quickly adjust his belt in order to support himself in a convenient position in relation to the seat of an aeroplane or other aerial craft, and so that by withdrawing or opening devices arranged on the belt for the purpose he can instantaneously detach himself from the aeroplane.

The nature and scope of my present invention will be more fully understood from the following description taken in connection with the accompanying drawings forming part thereof, in which:

Figure 1 is a side elevation showing one side of the cable connection to an aeroplane fuselage;

Fig. 2 is a plan view to a smaller scale showing the complete attachment generally;

Fig. 3 is a partial side view of Fig. 2;

Fig. 4 is a front view of the belt or harness proper, as seen opened out when detached from the aviator; and

Fig. 5 is a modified form of device for quickly detaching the belt from its supports.

Referring first to Figs. 1 and 2, *a*, *b* represent two rails of an aeroplane fuselage; *c*, *d* are two cables, of which *c* attached by

the link *H* to the belt *A* passes backward to a fitment *g* and returns alongside the rail *a*, being finally hooked on to the cleat *e* by means of the eye-bolt *o*.

Similarly the cable *d* passes backward to the fitment *h* and returns along the rail *b* to be hooked on the cleat *f*. *g*' are holding down cables.

The cleats *e* and *f* are arranged conveniently alongside the pilot, or observer, for his normal position, and other cleats *u* and *v* are placed farther back as shown, so that in the event of the wearer wanting more freedom for a temporary purpose, or otherwise, he will simply unhook the cables from *e* and *f* and place them on *u* and *v*; with a distance of about six inches say, between the cleats *e* and *u*, this will allow of the aviator quickly having a further forward play of six inches; other cleats may be provided if desired.

Fig. 1 shows a means of connecting the cable *c* with the eye-bolt *o* so that its length is adjustable. *p* is a nut threaded on the eye-bolt *o* and having perforated wings to which the two ends of a loop *q* are attached, a tubular piece or bend *r* being threaded on the bend of the loop so as to strengthen it where attached to the end of the cable *c*. *s* is a spring tongue closing the mouth of the cleat so that the eye-bolt shall be kept in place when the cables are slack.

Fig. 3 illustrates the belt or harness on the aviator to which the cables *c* and *d* connect by means of the divided ends *j* attached to the double looped nuts *i*.

A is the chest pad which may either be integral with the extensions *C*, for instance if wholly of leather, or it may be made of elastic material connected by the jointing pieces *B* with the ends *C*. *M* is a shoulder strap provided with press button clasps *N* (two each side) which allow of the belt being adjusted at three different heights by attachment to a press button on each side of the pad, according to which clasps are used.

The connection to the stay ropes *j* which may advantageously be held by the slings *w* always near the seat *x* is by means of the links *H* with threaded shanks which are threaded into winged nuts *i* formed with loop wings to which the cable end *j* is attached after passing through the sling rings.

- 2 *w*; these links H are connected to the belt by end pieces D doubled back and terminating in a loop which is secured in the hinge piece E by the detachable pin G; the pins G are secured by cords F and this is common practice but a material advantage resides in the novel doubled back connection to the link H, in that the strain on the pin G is reduced to half that it would have if a direct connection is made, and friction of the material at the bend also tends to lessen the strain, the pins in consequence being much easier to get out when there is weight on the belt.
- 10 15 To adjust the length of the stay ropes the links H are detached and turned in or out of the nuts i, according to the adjustment required, and this can be done very quickly.
- 15 20 Fig. 5 illustrates a modified form of fastening for the turned back end D; it is provided with a link I which passes over a lever J pivoted at K K in the known two-position manner, the pivot plate supporting the pivots K K being firmly stitched to the part C and the pivot ends of the lever J being formed with lugs, or miniature levers, which serve in conjunction with the spring of the pivot support to keep the lever J in the closed or open position, as set.
- 25 30 The pad A may be of either elastic or non-extensible material; the position on the chest is desirable as the aviator is best able to take a shock there, say of a bad landing, or of a smash.
- 30 35 The aviator by means of this invention may quickly gain a freedom of movement equal to the distance apart of the cleats e, u, precise adjustments for his normal position being made by the eye-bolt o or the nuts a.
- 35 40 The ability to gain extra freedom suddenly is of great importance in the case of a gunner, say on an aeroplane as otherwise he might have to disconnect his belt altogether.
- 40 45 Rings w or similar provision may be made for securing the belt ends of the cables c d easily within reach of the aviator for re-attachment after disuse.
- 45 50 The several features of the present invention are not limited to the precise construction and arrangement of devices described, and many modifications and changes may be made therein without departing from the spirit of this invention; for instance, hooks might be used instead of the eye-bolts o and holes in a bracket corresponding to the cleat e; also a hook for the belt connection j.
- 50 55 Further, a single cable with duplicate ends and one set of cleats might be employed if bifurcated far enough back from the aviator.
- 55 60 Having thus described the nature and objects of my invention, what I claim as new and desire to secure by Letters Patent is:—
- 60 65 1. An adjustable support for aviators consisting of a belt or harness having a link attached to each end of same, a cable from each said link and an eye-bolt thereon at its other end, means for supporting a bend in each cable whereby it is doubled back 70 toward the aviator, and two or more cleats attached to the aircraft on each side and within easy reach of the aviator to which the said eye bolts are connected.
- 70 75 2. An adjustable support for aviators consisting of a belt or harness having links attached to its ends, a doubled back length of the belt at each end inclosing said link, means for securing the doubled back length at each end so as to be readily unfastened, a 80 cable from each said link and an eye bolt thereon at its other end, means for supporting a bend in each cable whereby it is doubled back toward the aviator, and two or more cleats attached to the aircraft on each side and within easy reach of the aviator to which the said eye bolts are connected.
- 80 85 3. An adjustable support for aviators consisting of a belt or harness having links with threaded shanks attached to the ends of 90 same, nuts on the said shanks, cables attached to the said nuts, threaded eye bolts, nuts on the said eye bolts, cables attached to the eye bolt nuts, means for supporting a bend in each cable whereby it is doubled 95 back toward the aviator, and two or more cleats attached to the aircraft on each side and within easy reach of the aviator to which the said eye bolts are connected.
- 95 100 4. An adjustable support for aviators consisting of a belt or harness having a link attached to each end of same, a cable from each said link and an eye bolt thereon at its other end, adjustable means for connecting up the cable at either end, a bracket and support located behind the aviator for supporting a bend in each cable, two or more cleats on the air craft body adjoining the aviator's seat on each side, flexible tongues closing the mouth of said cleats, and an adjustable 105 shoulder strap attachment to the belt, all substantially as and for the purpose set forth.
- 105 110 5. In an adjustable support for aviators the combination with a belt or harness having a link attached to each end of same, of cables detachably connecting the said links with the air craft body, a doubled back length of the belt at each end inclosing the said link, a loop fastening on the loose 115 doubled back end and on the belt respectively, and a pin connecting the loop fastenings.
- 115 120 6. In an adjustable support for aviators the combination with a belt or harness having a link attached to each end of same, of cables detachably connecting the said links with the aircraft body, a doubled back length of the belt at each end inclosing the said link, means for securing the loose doubled 125 130
- 130 135 1. An adjustable support for aviators con-

back end so that it may be quickly unfastened, an adjustable shoulder strap supporting the belt on the wearer, and two or more press button connections between the said strap and the belt.

7. In an adjustable support for aviators, the combination with a belt or harness having a link with a threaded shank attached to each end of same, of cables detachably connecting the said links with the aircraft body, a doubled back end of the belt at each end inclosing the said link, means for securing the doubled back end so that it may be quickly unfastened, and a cable connection to the said link comprising a nut on the threaded shank of same, looped wings on the nut, and loops on a bifurcated end of the

cable, all substantially as and for the purpose set forth.

8. An adjustable support for aviators consisting of a belt or harness having a link attached to each end of same, a cable from each said link and an eye bolt thereon at its other end, means for supporting a bend in each cable whereby it is doubled back toward the aviator, two or more cleats attached to the aircraft on each side and within easy reach of the aviator to which the said eye bolts are connected and an adjustable shoulder strap supporting the said belt, with two or more press button connections between the said shoulder strap and the belt.

In testimony whereof I affix my signature.
ALLIOTT VERDON ROE.
